HEARING AID CASING

Logan W. Johnson and John F. Rose, Minneapolis, Minn.,
assignors, by mesne assignments, to Maico Electronics
Inc., Minneapolis, Minn., a corporation of Minnesota

Application March 5, 1956, Serial No. 40,447

Term of patent 7 years

(Cl. D26—14)

Fig. 1 is a view in perspective of a hearing aid casing showing our new design, the same being seen from the front and one side and end;

Fig. 2 is a view in perspective showing the rear and opposite side and end of the casing of Fig. 1;

Fig. 3 is a view in front elevation; and

Fig. 4 is a view in end elevation as seen from the left to the right with respect to Fig. 1.

We claim:

The ornamental design for a hearing aid casing, as shown.
